UNITED STATES PATENT OFFICE.

ANGUS F. HANNEY, OF CINCINNATI, OHIO, ASSIGNOR TO THE AMERICAN LAUNDRY MACHINERY COMPANY, OF CINCINNATI, OHIO, A CORPORATION OF OHIO.

LAUNDRY-MARKING TAG.

Application filed July 18, 1927. Serial No. 206,521.

This invention relates to improvements in identifiers for attachment to articles to identify the same and particularly to such devices used in connection with laundry systems for attachment to the various articles to identify them according to any approved method of routing the articles through the various steps of a laundry process.

More specifically, this invention relates to an identifier of the jaw or clamp type adapted to be clamped upon the article beyond the edge thereof and to be removable therefrom but securely attached thereto so as to pass through the various machines used in the laundry.

The identifier of this application is of a type comprising a pair of spring clamping jaws rigidly joined, hinged or otherwise secured together and preferably of the self-opening type arranged so that a securing means for the jaws may be provided beyond the edge of the material to hold the identifier firmly in position upon the article.

Other features of the invention will be brought out in the following description, drawings and claims.

Referring to the drawings, Fig. 1 is a perspective view of the device; Fig. 2 is a view partly broken away; Fig. 3 is an enlarged cross section through the securing device and showing in dot and dash lines some of the tools used for setting the securing device; and Fig. 4 is a view of the identifier with the securing device set in position to hold the clamping jaws upon the article and indicating in dot and dash lines the tools for the removal of the holding device.

In the embodiment set forth in the drawings, the main clamping member comprises the body portion 1 and the clamping portion or jaw 2 preferably formed of a single strip of flat metal shown as of rectangular form. The body portion may be provided with suitable identifying recesses 3 and 4 which may cooperate with a suitably formed rack well known in this art. The body portion may also be provided with suitable identifying indicia indicated at 5.

Secured to the body portion is a strip 6 forming a part of another clamping member or jaw 7. This strip 6 is riveted, as at 8, to the body portion of the clamping member 2. It may be hinged to the body portion, as is well known in the art, it being preferable, in any case, to have the clamping portions or

jaws possess a normal tendency to open to facilitate application to and removal from the work.

One of the clamping portions or jaws, as for example the portion 2, may be provided with projections 9 for engagement in suitable openings 10 in the other clamping portion or jaw 7. These cooperating projections and recesses serve to provide a suitable bite upon the work to prevent its accidental removal from the identifier. Each of the clamping portions or jaws 2 and 7 is provided with an inner opening 11 and an outer enlarged recess 12, the arrangement being such that these openings and recesses can receive the shank and the flanges of a suitable fastening device in the form of a grommet or eyelet, as will appear.

The fastening device, which is in the form of a grommet or eyelet, comprises the shank 13 and fixed flange 14, this flange nesting in one of the recesses 12 and the shank being adapted to pass through the openings 11 of both of the clamping portions or jaws 2 and 7. The shank 13 is also provided with one or more inner projections 15 forming square shoulders 16 adapted for use in the removal of the grommet or eyelet, as will appear.

When the grommet or eyelet is inserted in the clamping portions or jaws, the outer end of the shank is swaged over to form a flange shown at the top in Fig. 4, for engagement in the other recess 12 of the other clamping portion or jaw. It is obvious that when the grommet or eyelet is being applied, as shown partially in Fig. 3, a suitable support 17, provided with an opening 18, will support the identifier and a punch 19 with a reduced shank 20 will serve to carry the eyelet down through the openings in the clamping portions or jaws ready for the lower end of the shank to be spread or swaged out against the suitably formed surface 21 provided about the opening 18 in the support 17.

By properly arranging the parts the grommet or eyelet will cause the clamping portions or jaws to be firmly clamped upon the article with the proper tension to produce and form a firm grip between the marker and the article. The article thus identified can pass freely through the machines in the laundering process and any machine exerting pressure upon the identifier, as for instance, an ironing machine, will tend to more firmly clamp the identifier upon the article and may, in

some cases, produce a further setting up of the eyelet and a more rigid clamping action between the identifier and the article.

When the identifier is to be removed it is placed in reversed position above a suitable support 22 provided with an opening 23 larger than the flanges of the grommet or eyelet.

Another plunger 24, having a pilot 25 of the size of the bore of the shank of the grommet or eyelet, is then caused to move down into engagement with the shoulders 16, whereupon the flange formed on the end of the shank of the eyelet will be turned back to shank forming position and the eyelet will readily pass out through the opening 23 in the support 22.

The identifier is then ready for re-use.

What I claim is:

1. A marker for repeated use on articles to be subjected to laundry and like treatment comprising a clamp having hinged jaws each having a clamping portion for engagement with the work, and aligned openings between the hinge and the clamping portions of the jaws and outside of the work engaging area thereof for the reception of a grommet for securing the clamp upon the work.

2. A marker as in claim 1 wherein the clamping jaws are uniformly flat throughout and are provided upon their outer sides with

recesses surrounding their grommet openings whereby the grommet, when applied, may firmly secure the marker upon the work without increasing the thickness of the marker.

3. A marker as in claim 1 wherein the clamping jaws are uniformly flat throughout and are provided upon their outer sides with recesses surrounding their grommet openings, and a grommet passing through said openings and having its flanges engaging in the recesses around the opening.

4. A marker as in claim 1 wherein the grommet openings are provided with a grommet for clamping the jaws upon the work, and means carried by the grommet for engagement by a tool for the removal of the grommet.

5. A marker as in claim 1 wherein the grommet openings are provided with a grommet for clamping the jaws upon the work, and means carried by the grommet for engagement by a tool for the removal of the grommet, and comprising a shoulder struck inwardly from the tubular portion of the grommet.

In testimony whereof I hereby affix my signature.

ANGUS F. HANNEY.
